DUST COLLECTOR

George E. Teasdale, New York, N. Y.

Application January 8, 1937, Serial No. 119,616

3 Claims. (Cl. 183—95)

This invention relates to dust collectors, and particularly to improved dust collectors for chimneys, the object being to provide a construction which may be readily mounted on any special or conventional chimney and act to prevent dust, sparks, and the like from being discharged into the open atmosphere above the chimney.

Another object of the invention is to provide a dust collector for chimneys wherein means are presented which will deflect the smoke and dust so that the movement of the smoke will be retarded during the change of direction and allow the dust to settle into a suitable hopper, while at the same time permitting the gaseous matter to move outwardly through the outlet of the device.

An additional object, more specifically, is to provide a dust collector for chimneys and the like wherein rotating means are presented actuated by the movement of the smoke or dust for breaking up or stirring any dust or foreign matter collected, whereby it may freely be discharged.

In the accompanying drawing:

Fig. 1 is a longitudinal vertical sectional view through the upper part of a chimney and a collector disclosing an embodiment of the invention, the section being taken on the line 1—1 of Fig. 2;

Fig. 2 is a sectional view through Fig. 1 approximately on the line 2—2.

Referring to the drawing by numerals, 1 indicates a chimney of any desired kind which is adapted to extend upwardly through the roof 2 of the building. In various buildings it is customary to have a chimney and to construct the chimney to project some appreciable distance 35 above the roof. Under some circumstances dust and sparks will pass out of the chimney and become more or less dangerous to surrounding property as well as be objectionable by reason of the discharge of dust, soot, and the like. To overcome 40 these objections a collector has been provided, as shown in the accompanying drawing, wherein dust and other foreign matter is collected and guided to a suitable receptacle while the gases are permitted to escape upwardly into the air.

As shown in Fig. 1, the chimney 1 is adapted to receive and support a hood 3 which is provided with a depending flange 4 snugly fitting over the upper end of the chimney and a tubular inlet 5 is formed to fit snugly within the flue 6 so that all smoke or other matter passing up through the flue will be discharged into the hood 3 before anything passes out of the outlet 7. The hood 3 and associated parts are preferably made from metal and may be secured in place by friction only 55 or by cement, bolts, or the like. The hood 3 is

preferably of the same general shape as the chimney 1, and as shown in the accompanying drawing is substantially rectangular with the outlet 7 set off slightly to the right of the inlet 5 as illustrated in Fig. 1.

A primary deflector 8 is arranged in the inlet 5 so as to deflect the dust, smoke, and the like to one side so as to heat the respective blades 9 of the propeller 10 as the propeller rotates. This propeller is rigidly secured to a shaft 11 journaled in a suitable journal tube 12. A stirring member 13 is also rigidly secured to the shaft 11, whereby whenever the propeller 10 rotates the stirring member 13 will rotate. This stirring member is preferably formed with a plurality of 15 stirring blades and each blade is preferably substantially triangular in cross section, whereby as it rotates it will stir and break up any dust or foreign matter collecting in the hopper 14 which is formed from part of the casing 3 and from an 20 inclined wall 15.

Extending from the inlet 5 is an auxiliary deflector 16 which extends in a general direction toward the outlet 7 although inclined from a straight line as shown in Fig. 1. The upper part 25 of the deflector 16 is arc-shaped and extends in a certain sense horizontally transversely of the outlet 7 so that smoke and dust striking the deflector will be deflected to the left as shown in Fig. 1, and then the gases or smoke are deflected to the right before they can pass out through the opening 7. A screen consisting of wire mesh 17 is arranged near and slightly above the point of second change of direction of the smoke. It will be noted that the smoke changes 35 direction twice and is thereby retarded somewhat at point 18, whereby any dust, dirt or foreign matter may drop by gravity in the hopper 14 and pass through the bottom of the hopper into the chute 18. The lower end of the chute 18 40 discharges into the casing 19 which contains a removable container 20 arranged normally beneath the discharge end of the chute 18. The casing 19 has a removable door 21 whereby the receptacle 20 may be inserted and removed whenever desired. A wire mesh covered vent opening 22 is also provided in casing 19.

As the chimney 1 functions to emit smoke and other foreign matter from a fire, the smoke and foreign matter will pass upwardly in a substantially vertical direction and strike the upper part 50 of the deflector 16. This will change the direction of the smoke, dust, and the like, and to a limited extent deflect the same downwardly as well as to the left as shown in Fig. 1. Also the 55

space at point 18 is greater than the passageway 23. This reduces the pressure and speed of the parts so that the dust and the like may readily drop down into the hopper 14 while the 5 gaseous matter will continue to rise and pass through the screen 17. Screen 17 is preferably rather fine wire mesh and consequently acts to stop a certain amount of dust and the like passing out through the opening 7.

10 As the smoke, dust, and the like moves upwardly into the hood 3, it will strike one of the blades 9 and rotate the propeller 10, which in turn will rotate the stirrer 13. As the smoke, dust, and the like continues to move upwardly 15 through the chimney, it will continually cause the propeller 10 and associated parts to move upwardly so that there will always be a full passage in the hopper 14 for any collected dust, dirt, or the like.

20 I claim:

1. A dust collector comprising a hood having a casing formed with a top having an outlet, a bottom having an inlet, outer depending flanges carried by said bottom and adapted to fit over the 25 top of a chimney and inner depending flanges adapted to fit into the flue of said chimney, said inner depending flanges extending from said bottom around said inlet, a plurality of walls in said casing extending from said inlet and forming 30 a passageway for deflecting the incoming smoke at right angles to the axis of said inlet, a screen between the outlet of said passageway and the outlet in the top of the casing, and means including part of said casing forming a dust collecting hopper below the discharge end of said 35 passageway.

2. A dust collector comprising a hood having a casing formed with an apertured top and an aper-

tured bottom and with outer depending flanges adapted to fit over the top of a chimney and inner depending flanges adapted to fit into the flue of said chimney, said inner depending flanges extending from said bottom around the perimeter 5 of said aperture in the bottom and forming an inlet from said chimney, a plurality of wall members extending generally upwardly from said inlet for presenting an arc-shaped generally flaring passageway with the opening positioned to 10 discharge smoke horizontally against one wall of said casing when the casing is positioned with the inlet extending vertically, a dust collecting hopper positioned substantially below that part of the wall of said casing struck by the smoke 15 discharged from said passageway, and a screen above said hopper extending from the top of the discharge opening of said passageway to the casing, said casing having a top wall above said screen for deflecting gases passing through said 20 screen to the aperture in the top of the casing which acts as an outlet.

3. A dust collector including a hood having an outer casing formed with an outlet in the top and an inlet in the bottom, means in said hood for forming a tortuous passageway for smoke passing from said inlet to said outlet, a screen extending across said passageway at one point, a dust collecting hopper positioned below said screen, a stirring member arranged substantially centrally 25 of said hopper, a shaft secured to said stirring member and extending into said passageway immediately above said inlet, and a bladed member actuated by smoke moving into said passageway, 30 said bladed member being rigidly secured to said shaft whereby when said shaft is rotated said stirring member will be caused to function.

GEORGE E. TEASDALE.
